UNITED STATES PATENT OFFICE

2,431,905

QUICK LOCKING FURNACE BASE PLATE

Robert J. Anicetti, Beverly, Mass., assignor to the
United States of America as represented by the
Atomic Energy Commission

Application March 16, 1945, Serial No. 583,129

3 Claims. (Cl. 220—40)

1

This invention relates to improvements in bottom closures for receptacles such as furnaces, crucibles and the like, and more particularly to an improved means for removably securing a bottom closure to a receptacle of the class described.

In receptacles of the type herein described, it is highly desirable to fill the receptacle from the top and to have the bottom removable to facilitate cleaning of the receptacle. The invention is shown applied to a furnace or crucible of cylindrical construction and an important object of the present invention is the provision of an improved bottom construction which may be applied to existing furnace structures.

A further object of the present invention is the provision of a bottom closure for furnaces and crucibles comprising a plate adapted to cooperate with raceways secured to the lower ends of a cylindrical wall member for ready assembly and disassembly.

A still further object of the present invention is the provision of a bottom closure for furnaces and crucibles which is relatively simple in construction, rugged and inexpensive to manufacture.

Other objects and advantages of this invention will be apparent during the course of the following detailed description.

In the accompanying drawing, forming a part of this specification, and wherein similar reference numerals designate corresponding parts throughout the several views:

Fig. 1 is an elevational view of the lower end of a furnace showing my improved closure structure applied thereto;

Fig. 2 is a section taken on the line 2—2 of Fig. 1;

Fig. 3 is an enlarged sectional view showing certain details of the improved bottom construction;

Fig. 4 is a front view of one of the raceways; and

Fig. 5 is a top view of the same.

In the drawing, wherein for the purpose of illustration only is shown a preferred embodiment of the invention, the numeral 10 designates a cylindrical furnace or crucible to which the present invention is applied. The furnace or crucible comprises inner and outer cylindrical wall members 11 and 12 and to these there is welded a bottom annular flange 13 as indicated at 14 and 15.

A plurality of raceways 16 are spaced at equal intervals circumferentially about the periphery of the flange member 13, and secured thereto as hereinafter described. In the present embodiment of the invention four such raceways are provided but it is clear that any number may be used

depending on the size of the furnace or crucible. Each raceway 16 comprises a rectangularly shaped member bent to conform to the radius of the furnace base flange 13. Suitable openings 17 are provided in the raceways 16 and pins 18 may be used to properly position the raceways for welding the same to the base flange 13. Each raceway 16 is provided with a laterally extending slot or runway 19 having its lower edge sloping upwardly in an inward direction.

Referring to Fig. 2, the bottom structure comprises a double walled member consisting of an upper plate 20 and a lower plate 21 welded to said upper plate. If desired, a cooling liquid may be provided in the space between the two plates. A plurality of threaded bolts 22 herein shown as four and corresponding to the number of raceways, are threaded into the periphery of the plate member 20 and are equidistantly spaced around the circumference of the bottom closure. A groove 23 is provided on the upper surface of the plate member 20 to receive a gasket 24.

To apply the bottom closure, it is placed between the raceways 16 with the bolts 22 facing the slots 19. A slight turn in a clockwise direction serves to engage the bolts 22 within the runways 19 and continued rotation of the bottom closure causes it to be firmly positioned against the base flange 13 in which position it may be secured by tightening the bolts 22. The sealing gasket 24 provides a proper seal between the upper plate 20 and the flange 13. To remove the closure, the bolts 22 may be loosened and then lightly tapped to free the closure, which then can be rotated easily so as to clear the raceways 16 and drop onto a stacker or other support (not shown).

From the above description, it is believed that the construction of the device will be clear to those skilled in the art and the advantages thereof are readily apparent. It is understood, however, that I do not confine myself to the structural details illustrated, and that certain changes can be made without departing from the spirit of the invention within the limitations of the appended claims.

I claim:

1. A furnace including, in combination, a cylindrical wall, an annular flange secured to an end of said wall, a plurality of depending raceways fastened at spaced intervals around the outer periphery of the annular flange, an inclined slot extending from a side of each of said raceways, a disk shaped closure member, an annular groove in said member, a deformable gasket carried in said groove adapted to engage the an-

2

nular flange, a plurality of bolts spaced about the periphery of the closure member and adapted to secure the closure member to said depending raceways and to provide a tight fit between said annular flange and said gasket.

2. A furnace including, in combination, a cylindrical wall, an annular flange secured to an end of said wall, a plurality of depending raceways fastened at spaced intervals around the outer periphery of the annular flange, an inclined slot extending from a side of each of said raceways, said slots converging at a constant rate inwardly from the sides of said raceways, a disk shaped closure member, an annular groove in said member, a deformable gasket in said groove adapted to engage the annular flange, a plurality of bolts spaced about the periphery of the closure member and adapted to secure the closure member to said depending raceways and to provide a tight fit between said annular flange and said gasket.

3. A furnace including, in combination a double cylindrical wall adapted to contain a fluid coolant therebetween, an annular flange secured to an end of said double wall and forming a fluid tight joint

therewith, a plurality of raceways fastened at spaced intervals around the outer periphery of the annular flange, an inclined slot extending from a side of each of said raceways, said slots converging at a constant rate inwardly from the sides of said raceways, a disk shaped closure member, an annular groove in said member, a deformable gasket in said groove adapted to engage the annular flange, a plurality of bolts spaced about the periphery of the closure member and adapted to secure the closure member to said depending raceways and to provide a tight fit between said annular flange and said gasket.

ROBERT J. ANICETTI.
